UNITED STATES PATENT OFFICE.

WILLIAM C. HUEBNER, OF BUFFALO, NEW YORK, ASSIGNOR TO HUEBNER-BLEISTEIN
PATENTS COMPANY, OF BUFFALO, NEW YORK.

PHOTOGRAPHIC-PRINTING APPARATUS.

1,216,318.

Specification of Letters Patent. Patented Feb. 20, 1917.

Application filed April 26, 1915. Serial No. 24,726.

To all whom it may concern:

Be it known that I, WILLIAM C. HUEBNER, a citizen of the United States, residing at Buffalo, in the county of Erie and State of New York, have invented a new and useful Improvement in Photographic-Printing Apparatus, of which the following is a specification.

This invention relates to photographic printing apparatus of the kind used for producing photographic prints upon the photo-sensitive or sensitized surfaces of metal plates or other material which are afterward suitably finished and used for printing in one or more colors. Such printing apparatus usually comprise a holder or support in which the sensitized plate is mounted so that its sensitized surface can be pressed against the transparent photographic printing plate or negative which is illuminated for making the print, and the holder for the sensitized plate or the transparent printing plate or both, is usually capable of adjustment parallel with the sensitized surface to enable one or more prints to be made in any required position and arrangement on the sensitized plate or prints to be made in registering position on different sensitized plates, as when the plates are to be used for multi-color printing.

The invention relates more particularly to the sensitized plate holders of such apparatus and has for one of its objects to provide a practical and desirable portable holder in which the sensitized plate can be readily secured before the holder is placed in the photographic printing apparatus, and which can be quickly and easily placed in a predetermined position on the adjustable support or carriage of the photographic printing apparatus, thus enabling the sensitized plate to be secured in the holder while the latter is out of the apparatus and can be conveniently handled or positioned for properly adjusting and stretching the plate therein, and also making it possible to secure a sensitized plate in one holder while prints are being made on another sensitized plate in another holder in the apparatus. In this way the plate holder in the apparatus can be quickly removed and replaced by another holder in which the sensitized plate has already been secured, thus permitting a much more rapid and convenient operation of the

apparatus than is possible with an apparatus in which the plate holder is not readily removable. The portable plate holder also enables the sensitized plate to be conveniently handled and properly positioned with reference to apparatus for performing other operations on the plate, such, for instance, as laying out and checking up the work, &c.

Another object is to produce a plate holder of improved construction in the respects hereinafter described and set forth in the claims.

In the accompanying drawings:

Figure 1 is a front elevation of a plate holder embodying the invention.

Fig. 2 is a fragmentary front elevation thereof and of the supporting frame for the plate holder, showing a different adjustment of the plate securing bars.

Fig. 3 is an elevation, enlarged, of a portion of one of the securing bars with the clamping strip removed.

Fig. 4 is a sectional plan view, enlarged, of a portion of the securing bar in line 4—4, Fig. 10.

Fig. 5 is an enlarged fragmentary rear elevation, partly in section, of the plate holder.

Fig. 6 is a plan view thereof.

Figs. 7, 8 and 9 are sectional plan views thereof in lines 7—7, 8—8 and 9—9, respectively, Fig. 5.

Figs. 10 and 11 are cross sections of the securing bar in lines 10—10 and 11—11, respectively, Fig. 4.

A represents the portable or removable plate holder in which the sensitized plate, shown at B, is secured and C represents a rectangular supporting frame or carriage on which the plate holder A is adapted to be removably mounted for holding the sensitized plate in operative relation to the transparent printing plate in the printing apparatus. The supporting frame or carriage C, which is a part of the printing or other apparatus in which the sensitized plate is to be operated upon, may be constructed and mounted in the apparatus in any usual or suitable manner, as for example, in the manner disclosed in application for U. S. patent, Serial No. 839,997, filed by me May 21, 1914, in which a similar supporting frame is shown in a photographic printing apparatus and arranged to be adjusted in two direc-

tions in a plane parallel with the sensitized surface.

The plate holder A may be removably retained in place on the supporting frame 5 by pins or studs 10 which project from the face of the supporting frame C into registering holes 11 in the plate holder A, or by any other suitable means adapted to hold the plate holder A in a predetermined position 10 on the supporting frame and allow it to be quickly and easily placed in position on and removed from the supporting frame.

The plate holder comprises a rectangular frame composed of longitudinal or side 15 bars 12 connected by end bars 13, relatively adjustable clamping or securing bars 14 and 15 to which the opposite edges of the sensitized plate B are adapted to be secured, and means for stretching or tightening the sensitized plate. As shown, the securing bar 14 is pivoted at its ends to guide blocks 16 which surround and are adapted to slide on the end bars 13 of the holder frame, and the other securing bar 15 is likewise pivoted at 25 its ends to guide blocks 17 slidably engaging the end bars 13 of the holder frame. The securing bar 14 is adapted to be secured in different positions on the end bars 13 nearer to or farther from the other securing 30 bar, as may be necessary to suit sensitized plates of different widths, by suitable means, such for instance, as screws 18 carried by the guide blocks 16 and adapted to enter seats or depressions 19 provided at intervals along the end bars 13. The other securing bar 15 is preferably moved on the end bars 13 toward and from the securing bar 14 by adjusting screws 20 which extend parallel with the end bars and are journaled 40 and held from endwise movement in bearings 21 and 22 on the holder frame and turn in screw-threaded holes in the guide blocks 17 of the securing bar 15. After the edges of the sensitized plate have been secured to 45 the two securing bars 14 and 15, the plate can be stretched or made taut by turning the adjusting screws 20 to move the bar 15 away from the bar 14. The pivotal joints between the securing bars 14 and 15 and their guide 50 blocks enable the bars to swing angularly to some extent without causing the guides to bind on the end bars 13. The adjusting screws 20 can therefore be operated singly without causing the bars to bind, and the 55 bars can be adjusted out of parallelism, if necessary, to properly stretch the sensitized plate. The securing bar 14 can be set so as to locate the edge of the printing plate secured thereto in a predetermined required 60 relation to the plate holder and the apparatus in which the plate is to be used, and the plate can then be stretched without disturbing this relation by the proper adjustment of the other securing bar 15.

23, Fig. 2, represents screws which con-

nect the securing bars 14 and 15 between their ends to the adjacent bars 12 of the holder frame for preventing the securing bars from springing inwardly between their ends and thus permitting the sensitized plate 70 to sag between its ends. The screws 23 shown are passed through smooth holes in the securing bars. Screws 23 of different lengths can be used with plates of different widths, so that the screws will not project 75 to an objectionable extent beyond the securing bars. These screws can be used or not, as required, or other suitable means substituted therefor.

Each of the securing bars 14 and 15 has 80 secured on its outer or front face, which preferably inclines rearwardly from its inner edge, a clamping strip 25, between which and the face of the securing bar the edge of the sensitized plate is adapted to 85 be inserted; the clamping strip being preferably rabbeted to form a receiving recess 26, see Figs. 10 and 11, for the edge of the sensitized plate. The edge of the sensitized plate is gripped between the clamping 90 strip 25 and a series of eccentrics or rollers 27 which are located at intervals along the securing bar in pockets therein. The rollers have eccentric journals 29 at their ends which are seated in bearings formed by a 95 slot 30 which extends lengthwise in the front side of the securing bar intersecting the roller pockets. The rollers are placed in their pockets before the clamping strip 25 is fastened on the bar and are retained in place 100 by this strip. Each roller has a pin or handle 31 extending rearwardly therefrom by which it can be turned to grip and release the sensitized plate. The securing bars could be provided with means of other construction for clamping or securing the edge 105 of the sensitized plate thereto, but the described clamping means can be quickly and easily operated to grip and release the plate, they are very efficient in action, and are of 110 simple and durable construction.

I claim as my invention:

1. A portable holder for a printing plate having a sensitized surface, said holder comprising an open frame, and means carried 115 by the frame for securing and stretching the sensitized plate thereon, whereby said holder is adapted to be placed in and removed from a photographic printing apparatus with the sensitized plate in place 120 thereon, provision being made for placing said holder in a predetermined position in the apparatus.

2. A portable holder for a printing plate having a sensitized surface, said holder comprising an open frame, and substantially 125 parallel bars mounted on said frame and provided with means for securing the sensitized plate thereto, one of said bars being adjustable on the frame toward and from the 130

40

other bar, said holder being adapted to be placed in and removed from a photographic printing apparatus with the sensitized plate in place thereon.

5 3. The combination with a supporting frame, of a portable holder for a printing plate having a sensitized surface, said holder comprising an open frame, and means carried thereby for securing and tightening the sensitized plate thereon, whereby the holder with the sensitized plate in place thereon is adapted to be placed on and removed from said supporting frame, and co-operating parts on said supporting frame and plate 10 holder for holding the latter in a predetermined position on the face of said supporting frame.

15 4. The combination with a supporting frame, of a portable holder for a printing plate having a sensitized surface, said holder comprising an open frame, and means carried thereby for securing and tightening the sensitized plate thereon, whereby the holder with the sensitized plate in place thereon is 20 adapted to be placed on and removed from said supporting frame, and studs projecting from one of said frames and adapted to enter holes in the other frame for holding the plate holder in a predetermined position 25 on the supporting frame.

30 5. A holder for a printing plate comprising an open frame, substantially parallel securing bars mounted on said frame and provided with means for securing the printing plate thereto, guide blocks to which one 35 of said bars is pivoted at its ends and which are slidably mounted on said frame for adjusting said bar toward and from said other

bar, and means for securing said adjustable bar in adjusted positions.

6. A holder for a printing plate comprising an open frame composed of connected side and end bars, substantially parallel securing bars slidably mounted on said end bars and provided with means for securing the printing plate thereto, means for securing one of said securing bars to said end bars in different fixed positions relative to the side bars of said frame, and means for adjusting the other securing bar on the frame relative to the first securing bar for 45 tightening the printing plate.

7. A holder for a printing plate comprising an open frame, means thereon for securing one edge of the printing plate, a securing bar for the opposite edge of the printing plate, guide blocks to which said bar is pivoted and which are slidably mounted on said frame, and means for moving said guide blocks for tightening the printing 50 plate.

8. A holder for a printing plate comprising an open frame, means thereon for securing one edge of the printing plate, a securing bar for the opposite edge of the printing plate, means connected with the end portions of said bar for moving the bar to tighten the printing plate, and screws connecting said bar between its ends to the frame to prevent the bar from springing.

Witness my hand this 27th day of April, 1915.

WILLIAM C. HUEBNER.
